UNITED STATES PATENT OFFICE.

HERBERT E. WHITE, OF NEW YORK, N. Y.

MACHINE FOR FOLDING AND INSERTING SHIRRING-STRINGS INTO INCANDESCENT MANTLES.

SPECIFICATION forming part of Letters Patent No. 619,375, dated February 14, 1899.

Application filed August 19, 1898. Serial No. 688,968. (No model.)

To all whom it may concern:

Be it known that I, HERBERT E. WHITE, of New York city, (Brooklyn,) county of Kings, and State of New York, have invented an Improved Machine for Folding and Inserting Shirring-Strings into Incandescent Mantles, of which the following is a specification.

This invention relates to a machine which first turns down the upper end of the web of an incandescent mantle and then radially folds such doubled upper end and connects the several folds by an encircling thread. Thus the manipulations of folding and inserting a shirring-string into the mantle which have heretofore been performed by hand at considerable cost of skilled labor are by my machine performed automatically in a quick and accurate manner.

The construction and mode of operation of my machine will appear more fully from the accompanying drawings, in which—

Figure 1 is a perspective view of the upper part of a mantle which is turned down, folded, and has the shirring-string inserted by my improved machine. Fig. 2 is a side elevation, partly in section, of the machine complete; Fig. 3, a front elevation, partly in section, thereof; Fig. 4, a side elevation of the machine, showing the parts in a different position; Fig. 5, a plan of the machine; Fig. 6, a cross-section on line 6 6, Fig. 4; Fig. 7, a cross-section on line 7 7, Fig. 4; Fig. 8, a bottom view of the machine-head; Fig. 9, a top view of the barrel b. Figs. 10 and 11 are similar views showing the folder in different positions; Fig. 12, a section on line 12 12, Fig. 11; Fig. 13, a vertical section of the machine-head and the upper part of the barrel, showing said parts in engagement; and Fig. 14, a cross-section on line 14 14, Fig. 13.

The letter a represents the bed-plate of the machine, from which project upwardly side by side a revoluble barrel b and a fixed tubular standard c. The barrel b is of a diameter to permit a mantle to be drawn over the same, and it terminates on top in a number of fingers b', separated by slots b² and corresponding in number to the number of folds which are to be formed around the mantle.

The barrel b surrounds a fixed tube d of substantially the same height and having a single lateral slot d'. This slot permits the

outward passage of a movable finger or folder e, having opening e² at its outer end for the passage of the needle and eccentrically pivoted at e' to a revoluble shaft f, inclosed by tube d, so that the revolution of the shaft f causes a radial outward motion of the folder. The periods of revolution of the barrel b and shaft f are so timed that the latter makes a complete revolution while the former makes a fraction of a revolution equal to the distance between the centers of two adjoining slots b². Thus as the barrel b is revolved the folder e will pass outward and inward through each of the successive slots b² to form the folds in the mantle which is drawn over the barrel b, as hereinafter more fully described.

The barrel is shown to be revolved by hand-crank g, upon the shaft g' of which is mounted pinion g², engaging circumferential gear g³, fast on barrel b. Upon the shaft g' is, furthermore, mounted a large gear-wheel g', which by transmission-gears g⁵ g⁶ g⁷ revolves shaft f in the manner hereinbefore described.

Over the upper end of barrel b there is adapted to be projected the vertically-movable head of the machine which carries the folding-fingers, the needle, and the needle-guard, such head being attached to a cross-arm h of a vertical rod h', which slides in tube c and which is held against revolution by groove h² and spline c'. The head may be raised and lowered by suitable means—such, for instance, as a stirrup i and chain i', which passes over pulley i² and is connected to a pin h³ of rod h'.

The head of the machine consists, essentially, of a tubular needle-holder j, an inclosed revoluble lapping device k, and a surrounding tubular revoluble needle-guard l.

The lapping device k is provided at its lower end with two concentrically-placed circular rows of fingers k' k², the fingers of each row corresponding in number and position to the fingers b' of barrel b, the latter being received between the fingers k' k² as the head of the machine is lowered upon the barrel. The lapping device k may be revolved directly from barrel b by means of projections b³ on the barrel, which enter opposite slots between fingers k'.

The needle-holder j carries at its lower end a spiral needle m, which embraces the outer

fingers k^2 and is of such a length, preferably, that its eye-pointed end overlaps its root, Fig. 3. A circular adjustment of the needle-holder j and needle m may be obtained by slackening a set-screw j' , which binds the needle-holder to the cross-arm h , and then setting such holder by means of a handle j^2 .

The needle-guard l embraces the needle-holder j and is held and guided thereon by circumferential groove l^3 on the needle-holder, which is engaged by a pin l^4 of the needle-guard. The lower end of the needle-guard l terminates in fingers l^2 , which embrace the needle m and prevent an outward bending or displacement of the same under tension. The fingers l^2 correspond in position to the fingers $k' k^2$, as well as to the fingers b^2 , so that the slots between the several circles of fingers are always in radial alinement. A slotted screw l^3 on one of the fingers l^2 is adapted to hold the needle-thread when the needle is withdrawn from the web.

The needle-guard l is revolved in unison with thelapping device k and preferably directly from the same. The transmission is shown to be a gear-wheel n , fast on spindle k^3 oflapping device k and meshing into pinion n' , fast on shaft n^2 , which carries also pinion n^3 , engaging external gear n^4 , fast on circumference of needle-guard l . A spring-pin o , carried by an arm k^4 of spindle k^3 , enters at each revolution a shallow socket h^4 of cross-arm h to announce a complete revolution of the machine.

The operation is as follows: The machine-head is raised by stirrup i , and the mantle A to be folded and to be provided with a shirring-string is slipped over barrel b , a part of the mantle projecting above the fingers b' , Fig. 4. The machine-head is now lowered so that the fingers $k' k^2$ will embrace the fingers b' and the inner fingers k' will push the projecting or free end of the mantle down into the barrel, thus forming the doubled upper end A' , Fig. 13. The handle g is now turned to simultaneously revolve barrel b ,lapping device k , and needle-guard l , together with mantle A , and to also actuate the folder e by revolving the shaft f . The result will be that the folder e will pass rapidly outward and backward through successive radial slots that are formed by the radially-placed fingers $k' b' k^2 l^2$. In this way a series of folds are successively formed in the revolved mantle directly in front of the point of fixed needle m , which point is placed a short distance behind the path of the folder. As the mantle continually revolves these folds A^2 are, by the folder e , which has also an oscillating in addition to its radial motion, Figs. 9 to 11, pushed upon the needle which enters the eye e^2 . Thus the needle passes through the successive folds, Fig. 2, and connects them circumferentially by means of the asbestos needle-thread B . Upon a complete revolution of the barrel b the asbestos thread is severed by a knife p and its end drawn out and fas-

tened to the screw l^3 by being slipped into the nick of said screw or by looping it around the same. The machine is reversed to withdraw the needle, leaving the severed end of the thread attached to the screw, so that the thread remains in the web and is not withdrawn by the needle. The head is then raised and the mantle stripped off the barrel b , after which the operation is completed and the machine ready for the next mantle.

In lieu of making the mantle revoluble and the needle stationary, as described, it is evident that the needle may be made revoluble and the mantle stationary.

It will be seen that by my machine the mantles are turned down, folded, and provided with a shirring-thread automatically in a simple, rapid, and uniform manner and without the use of skilled labor, thus greatly improving their construction and cheapening their manufacture.

What I claim is—

1. In a machine for folding and inserting shirring-strings into incandescent mantles, the combination of means for supporting a mantle, with means for turning down its end, means for forming folds in the doubled mantle end, and means for drawing a thread through such folds, substantially as specified.

2. In a machine for folding and inserting shirring-strings into incandescent mantles, the combination of means for supporting a mantle, with a lapping device for turning down the mantle end, a folder for forming folds in the doubled mantle end, and a curved needle adapted to engage said folds, substantially as specified.

3. In a machine for folding and inserting shirring-strings into incandescent mantles, the combination of a slotted mantle-supporting barrel, with a folder adapted to move outward through the barrel-slots and form radial folds, and a needle adapted to engage such folds, substantially as specified.

4. In a machine for folding and inserting shirring-strings into incandescent mantles, the combination of a slotted mantle-supporting barrel, with a vertically-movable slotted lapping device for turning down the mantle end, a radially-movable folder to form folds, and a needle adapted to engage said folds, substantially as specified.

5. In a machine for folding and inserting shirring-strings into incandescent mantles, the combination of a slotted mantle-supporting barrel, with a folder movably secured within the barrel and adapted to move radially outward through the barrel-slots to form radial folds, and with a needle adapted to engage said folds, substantially as specified.

6. In a machine for folding and inserting shirring-strings into incandescent mantles, the combination of a slotted mantle-supporting barrel, with an inclosed revoluble shaft, a folder eccentrically pivoted to said shaft and adapted to move radially outward through the barrel-slots, to form radial folds, and with

a needle adapted to engage said folds, substantially as specified.

7. In a machine for folding and inserting shirring-strings into incandescent mantles, 5 the combination of a slotted mantle-supporting barrel, with a reciprocating folder, a lapping device adapted to be projected over the barrel, a needle-holder, and a curved needle secured to such holder, substantially as specified.

8. In a machine for folding and inserting shirring-strings into incandescent mantles, the combination of a mantle-supporting barrel, with a reciprocating folder, a lapping device 15 adapted to be projected over the slotted barrel end, a needle placed at the outside of said lapping device, and a needle-guard embracing the needle, substantially as specified.

9. In a machine for folding and inserting shirring-strings into incandescent mantles, 20 the combination of a slotted mantle-supporting barrel, with a reciprocating folder, a slotted lapping device adapted to be projected over the slotted barrel end, a needle-holder 25 embracing the same, a curved needle secured to the needle-holder, and a slotted needle-

guard embracing said holder, substantially as specified.

10. In a machine for folding and inserting shirring-strings into incandescent mantles, 30 the combination of a slotted mantle-supporting barrel, with a reciprocating folder, a lapping device having two concentric rows of fingers adapted to be projected over the slotted barrel end, and a curved needle arranged 35 at the outer side of the lapping device, substantially as specified.

11. In a machine for folding and inserting shirring-strings into incandescent mantles, the combination of a slotted mantle-supporting barrel, with a reciprocating folder, a lapping device having two concentric rows of 40 fingers adapted to be projected over the slotted barrel end, a needle-holder surrounding the lapping device, a curved needle secured 45 to the needle-holder, and a slotted needle-guard surrounding said holder, substantially as specified.
